UNITED STATES PATENT OFFICE

163,067

RING OR SIMILAR ARTICLE

Mabel C. Redmond, San Francisco, Calif.

Application November 13, 1950, Serial No. 12,949

Term of patent 14 years

(Cl. D45—10)

To all whom it may concern:

Be it known that I, Mabel C. Redmond, a citizen of the United States of America, residing in the city and county of San Francisco, and State of California, have invented a new, original, and ornamental design for a Ring or Similar Article, of which the following is a specification, reference being had to the accompanying drawing, forming part thereof.

The figure is an isometric view of a ring embodying my new design, the bottom, opposite side and end being the same in appearance as the top, side, and end shown.

The dominant feature of my design for a ring of the configuration shown resides in the four contrasting depressed areas of the ring periphery in association with the four matching triangular depressions on each side of the ring.

I claim:

The ornamental design for a ring or similar article, as shown and described.

MABEL C. REDMOND.
